UNITED STATES PATENT OFFICE.

EMORY PHILLIPS AND LOUISE W. KLUGMANN, OF ST. LOUIS, MISSOURI.

DESIGN FOR A RECEPTACLE FOR MAKING COFFEE.

SPECIFICATION forming part of Design No. 34,271, dated March 26, 1901.

Application filed December 24, 1900. Serial No. 40,974. Term of patent 7 years.

To all whom it may concern:

Be it known that we, EMORY PHILLIPS and LOUISE W. KLUGMANN, citizens of the United States, residing at St. Louis, Missouri, have 5 invented and produced a new and original Design for a Receptacle for Making Coffee, of which the following is a specification.

Figure 1 is a side elevation of the receptacle for making coffee, showing our new design; and Fig. 2 is a bottom plan.

As shown in the drawings, the leading or material feature of our design consists of the inverted-cup-shaped foraminous receptacle 3, the imperforate wall 4, extending downwardly 15 from the foraminous portion and around its edge, the flat foraminous bottom 5, the imperforate wall 6 around the edge of the bot-

tom 5 and having the flange 7 extending downwardly outside of the wall 4, the hinge 8, connecting the flange 7 to the wall 4, the spring-catch 9, attached to the flange 7 and engaging the wall 4, and the ring 10, attached to the top of the receptacle 3. A bead 11 appears around the bottom between the foraminous portion and the imperforate portion. 20 25

We claim—

The design for a receptacle for making coffee, substantially as herein shown and described.

EMORY PHILLIPS.
LOUISE W. KLUGMANN.

In presence of—

DAVID J. HAYDEN,
JOHN RUECKERT.
